UNITED STATES PATENT OFFICE.

PERCY A. ROBBINS, OF HIGHLAND PARK, ILLINOIS.

ACOUSTIC TRANSFORMER.

Application filed April 1, 1927. Serial No. 180,296.

This invention relates to methods of and apparatus for converting the movements of a diaphragm into sound waves or vice versa, such as shown and described in my copending application No. 180,295 dated Apr. 1st, 1927. In the transformer described in that application I caused the vibrations of a diaphragm to be imparted to or received from a stream of a gaseous medium contacting 10 with the diaphragm, which medium is preferably, initially, in a state of compression and is allowed to expand after passing the diaphragm. After expansion the gaseous medium mingles with the atmosphere and 15 is lost. I was thus restricted to the use of a cheaply available gaseous medium, such as atmospheric air, whereas a gaseous medium of greater density will give better results.

20 My object in the present invention is to devise a method and apparatus whereby a denser gaseous medium may be employed without material loss of the medium to the atmosphere.

25 I attain my object by enclosing the mouth of the chamber in which the gaseous medium is allowed to expand with a thin flexible diaphragm of large area and by returning the gaseous medium to the chamber from 30 which it was originally forced to and past the diaphragm.

The invention is hereinafter described and illustrated in the drawing, which is a vertical section of the apparatus constructed in 35 accordance with my invention.

1 is a chamber, with which communicates a conduit 2 communicating with the smaller end of the horn-shaped chamber 3. The larger end of the horn-shaped chamber communicates with the annular chamber 4, with 40 which communicates a conduit 5 communicating with the chamber 6 which, in turn, communicates through an opening 7 with the interior of the chamber 1. To the outer 45 rim of the annular chamber is secured a thin, light diaphragm 15, preferably formed of paper, gold-beater's skin, celluloid, or other such material, it being important, however, that the diaphragm be substantially 50 air tight. A closed circuit is thus provided, through which a stream of a gaseous medium may be circulated. To effect such a circulation I provide the blower 8, which is shown as of the "Root" type, and which is

located within the chamber 6, the discharge 55 outlet of the blower communicating with the opening 7.

The chambers 1 and 6 are preferably padded interiorly, as indicated at 9, to absorb any vibrations due to the operation of 60 the blower.

Staggered baffles 10 are preferably provided in the upper part of the chamber 6 to also aid in suppressing pulsations due 65 to the operation of the blower.

Between the conduit 2 and the chamber 3 I provide a constricted throat 11. Preferably this throat is adjustable in cross sectional area. A simple method of providing 70 adjustability is to form the throat of a section of rubber tubing and to apply thereto a clamp 12, the movable member 13 of which is adapted to be actuated by the screw 14.

Baffles 16 positioned in staggered relationship form a zig-zag passage through the 75 chamber 1, and these diaphragms are preferably formed of a porous material. Means are provided for keeping these baffles constantly wetted. For this purpose I show the upper edge of each baffle as secured to the 80 sprinkler tube 17. These are supported by branch tubes 18, which extend through the top of the chamber 1 and are connected with a liquid supply pipe 19. Separate valves 20 are provided to control the flow through 85 each branch pipe.

A valve controlled pipe 21 provides means whereby the chamber 1 may be filled with a suitable gas. Preferably a pipe 22 leading from the chamber 1 communicates with the 90 interior of a gasometer 23 of ordinary type whereby constant pressure may be maintained within the chamber 1. As the gaseous medium moves in a closed circuit, and there is substantially no waste, a relatively 95 dense gas such as carbon dioxide or sulphur dioxide may be employed.

Save for the employment of the closed circuit, the operation of the device is substantially as in my co-pending application 100 hereinbefore referred to.

The gaseous stream enters the conduit 2 under pressure, carrying with it considerable moisture, which moisture is more or less condensed in passing through the throat 11. 105 Thereafter the gaseous medium expands in volume and in cross sectional area in passing through the chamber 3, and thence flows

to the pump to be compressed. At the small end of the horn-shaped chamber 3 the diaphragm 24 is positioned. This may be arranged as usual to either receive or impart vibrations and is shown as of the electromagnetic type commonly employed in loud speakers.

It will be understood, of course, that the device is equally useful in transforming 10 sound waves into mechanical movements of a diaphragm.

Many variations are, of course, possible of the means for circulating the gaseous medium which will fall within the scope of 15 my invention.

What I claim is:

1. The method of imparting vibrations from a vibratable diaphragm to the atmosphere or vice versa, which consists in employing 20 as the transferring medium a stream of a gaseous medium contacting with the diaphragm and moving in a closed circuit.

2. The method of imparting vibrations from a vibratable diaphragm to the atmosphere or vice versa, which consists in employing 25 as the transferring medium a compressed gaseous medium contacting with the diaphragm and moving in a closed circuit, expanding said medium into contact with a second larger diaphragm, and returning the gas for recompression.

3. The method of imparting vibrations from a vibratable diaphragm to the atmosphere or vice versa, which consists in employing 30 as the transferring medium a stream of compressed gaseous medium contacting with the diaphragm and moving in a closed circuit, causing the formation in said medium of liquid in a finely divided state prior to contact with said diaphragm, expanding said medium into contact with a second larger diaphragm, and returning the gas for recompression.

4. The method of imparting vibrations from a vibratable diaphragm to the atmosphere or vice versa, which consists in employing 45 as the transferring medium a stream of dense gaseous medium contacting with the diaphragm and moving in a closed circuit, expanding said stream in cross sectional area into contact with a second larger

diaphragm, and returning the gas for re-compression.

5. The method of imparting vibrations 55 from a vibratable diaphragm to the atmosphere or vice versa, which consists in employing as the transferring medium a dense gaseous medium contacting with the diaphragm and moving in a closed circuit, causing the formation in said medium of liquid in a finely divided state prior to contact with said diaphragm, expanding said stream in cross sectional area into contact with a second larger diaphragm, and returning 60 the gas for recompression.

6. An acoustic transformer comprising a chamber increasing in cross sectional area from one end towards the other, a vibratable diaphragm at the smaller end of the 70 chamber; a larger vibratable diaphragm closing the other end of the chamber; and means for continuously introducing a gaseous medium into the smaller end of the chamber and for withdrawing it from the 75 larger end for re-use.

7. The method of imparting vibrations from a vibratable diaphragm to the atmosphere or vice versa, which consists in employing 80 as the transferring medium a stream of compressed gaseous medium contacting with the diaphragm and moving in a closed circuit, causing the formation in said medium of liquid in a finely divided state prior to contact with said diaphragm, expanding said medium in volume of cross 85 sectional area into contact with a second larger diaphragm, and returning the gas for recompression.

8. An acoustic transformer comprising a 90 chamber increasing in cross sectional area from one end towards the other, a vibratable diaphragm at the smaller end of the chamber; a larger vibratable diaphragm closing the other end of the chamber; and means for continuously introducing a gaseous medium into the smaller end of the chamber and for withdrawing it from the larger end for re-use including a conduit having a 95 constricted throat communicating with the smaller end of the chamber.

Signed at Highland Park, Ill., this third day of March, 1927.

PERCY A. ROBBINS.
